UNITED STATES PATENT OFFICE

122,963

DESIGN FOR A SEWING MACHINE OR THE LIKE

Malcolm S. Park, Mount Kisco, N. Y., and Hans
Hacklander, Linden, N. J., assignors to The
Singer Manufacturing Company, Elizabeth,
N. J., a corporation of New Jersey

Application October 12, 1939, Serial No. 87,638

Term of patent 14 years

To all whom it may concern:

Be it known that we, Malcolm S. Park and
Hans Hacklander, citizens of the United States,
residing, respectively, at Mount Kisco, New York,
and at Linden, New Jersey, have invented a new,
original, and ornamental Design for Sewing Ma-
chines, or the like, of which the following is a
specification, reference being had to the accom-
panying drawings, forming a part thereof.

Fig. 1 is a right side elevational view of a
sewing machine showing our new design.

Fig. 2 is a rear view of the same.

Fig. 3 is a front elevational view of the same.

Fig. 4 is a top plan view of the same.

We claim:

The ornamental design for a sewing machine
or the like, as shown.

MALCOLM S. PARK.
HANS HACKLANDER.
